Inventor;

S. H. Kennedy

S. H. KENNEDY, OF HYDETOWN, PENNSYLVANIA.

Letters Patent No. 83,712, dated November 3, 1868.

IMPROVEMENT IN MACHINE FOR FORMING SHEET-METAL PANS.

The Schedule referred to in these Letters Patent and making part of the same.

To all whom it may concern:

Be it known that I, S. H. KENNEDY, of Hydetown, Oil Creek township, county of Crawford, and State of Pennsylvania, have invented an Improved Machine for Forming Sheet-Metal Pans of rectangular form; and I do hereby declare that the following is a full, clear, and exact description thereof, reference being had to the accompanying drawings, which form a part of this specification, and in which—

Figure 1 is a top view of the machine, spread open ready for the insertion of the sheet-metal;

Figure 2 is a transverse section on line A B of fig. 1, showing the machine with the sheet-metal inserted and clamped down ready for bending;

Figure 3 is a transverse section on line C D; and

Figure 4 is a longitudinal section of one end of the bending-bar, taken on line E F of fig. 1.

A is a supporting-bar or bed-plate, to which the other parts of the machine are attached, and when in use, it should be bolted, or otherwise secured firmly to the bench of the workman.

A bending-bar, B, is hinged to one edge of the bed-plate A, and a clamp-bar, C, is hinged to the opposite or outer edge of the bending-bar B, all as shown. After the sheet-metal is inserted, the clamp-bar C is pressed down upon it, and held firmly in place by means of the pivoted lever D, by which, also, the bending-bar is turned up, as shown in fig. 2.

Thus far, my machine is not materially different from others which have heretofore been made.

The object of my invention is to so arrange and construct the machine, that it shall be capable of forming the sides and angles of rectangular sheet-metal pans at one operation, and be adaptable, by a slight change of parts, to all the different sizes of pans in ordinary use, thus avoiding the present necessity of a separate machine for each size of pan.

For forming the corners of the pans, a forming-piece, a, is cast upon each end of the bed-plate, and with a bevelled surface, b, projecting therefrom. At each end of the bending-bar B, a bevelled forming-surface, c, is provided, so arranged that as the sheet-metal is bent, by turning up the bending-bar B, the surplus metal at the corners of the pan shall be pressed or pinched together by and between the forming-surfaces b and c.

In order that pans of various sizes may be made upon the same machine, I provide a detachable end-former, a', with a bevelled forming-surface, b', and I so arrange that it may be attached firmly to the bed-plate A, (by means of a groove and thumb-screw, or in any other convenient manner,) at as many points along the upper surface of said bed-plate as the dimensions of the various sizes of pans may require, say four or five sizes.

In the bending-bar B, I provide a series of grooves or channels, d d, of sufficient width and depth to receive the surplus metal, and the projecting portion b'

of the detachable end-former a', (in whichever position it may be placed,) as the bending-bar is turned up. Within said grooves d d are bevelled forming-surfaces c' c', parallel with and similar to the forming-surface c, upon the end of the bending-bar; these forming-surfaces c' c' being so arranged as to operate in connection with the forming-surface b' on the detachable end-former a', in whichever position it may be attached to the bed-plate.

I provide a sliding gauge, e, upon the bending-bar, which gauge may be set in any position, parallel with the edge of the clamp-bar, to give the required depth of pan.

Under the above-described arrangement of parts, a single machine is capable of forming pans of any desired size and depth, limited only by the length of the bed-plate and bending-bar; but a separate clamp-bar, C' C', must be furnished for each size of pan required, and to allow of the ready attachment of said clamp-bars of different lengths, extra hinges are cast upon one end of the bending-bar, as shown.

The position of the pivoted lever D should be at or near the centre of the clamp-bar, and I make provision for it on the bending-bar, as shown at f. The different lengths of clamp-bars, and the positions of the detachable end-former a', are shown in dotted black lines in fig. 1.

The red lines in fig. 2 show the position of the machine after the metal is bent, and the blue lines represent the position of the sheet-metal during the process.

In making pans of the largest size, the longest accompanying clamp-bar C' is used, the detachable end-former a' is removed altogether, and the corners are formed between the surfaces b and c. When a smaller size is required, it is only necessary to change the clamp-bar for one of the required length, and attach the end-former a' to the bed-plate.

It will be observed that in forming the ends or shortest sides of the pans, the end-formers are not used, but the metal is simply bent between them. The corners of the pans are formed when bending the remaining two sides.

In peculiar cases, it may be desirable to make pans of other than rectangular form, in which case my machine can be readily adapted to all varieties of angular pans.

Having thus described my improved machine, What I claim as my invention, and desire to secure by Letters Patent, is—

1. In combination with the bed-plate A, the detachable end-former a', arranged to operate in connection with the forming-surfaces c' c', upon the bending-bar, substantially as and for the purposes set forth.

2. In the construction of the bending-bar B, the described arrangement of the forming-surfaces c' c', (one or more, as may be required,) to operate in connection with the detachable end-former a' upon the

bed-plate, substantially as and for the purposes set forth.

3. The general arrangement and combination of the bed-plate A, provided with its detachable end-former a', the bending-bar B, with its channels d d, and forming-surfaces c' c', skeleton clamp-bars C C, and bending-lever D, all arranged to co-operate sub-

stantially in the manner and for the purposes set forth.

S. H. KENNEDY.
